COPYHOLDER

Philip P. Glassey, Manlius, N. Y., assignor of one-third to Theodore E. Simonton, Cazenovia, N. Y.

Application April 29, 1939, Serial No. 270,894

14 Claims. (Cl. 120—34)

My invention relates to improvements in copyholders of the movable marker type.

The principal object of my invention is to provide a light, sturdy copyholder of simple and economical construction which is adapted to support the copy behind a typewriter with an operating key located adjacent the space bar of the typewriter.

A further object of my invention is to provide a construction in which the majority of the parts may be formed of sheet metal by stamping or pressing.

Another object of my invention is to provide an operating means for the movable marker which is positive in action, which is infinitely variable within defined limits to change the marker spacing adjustment correspondingly, and which includes a key having constant amplitude of movement regardless of change in the spacing setting of the marker so that the operator may readily become accustomed to the touch of the mechanism.

Still another object of my invention is to make the marker spacing adjustment means readily accessible by locating it at the operating key.

A further object of my invention is to provide a marker spacing adjusting means that may be adjusted with one hand.

Another object of my invention is to provide a copyholder, the easel of which may be readily folded down upon the base for storage and shipment.

Still another object of my invention is to provide spring return means for the marker operating mechanism that is so constructed and arranged as to maintain substantially constant the finger pressure required for operating the mechanism regardless of the marker spacing setting.

Other objects and advantages of my copyholder will become apparent from the following specification and the accompanying drawings, in which:

Figure 1 is a perspective view of my copyholder. Figure 2 is a side elevation of my copyholder in the operating position, parts being broken away.

Figure 3 is a side elevation of my copyholder folded in the storage position.

Figure 4 is an elevation of the easel taken on the line 4—4, Figure 2, parts being broken away.

Figure 5 is a plan view, partly in section and parts being broken away, taken on the line 5—5, Figure 2.

Figure 6 is a detail of the clutch box and easel taken on line 6—6, Figure 4.

Figure 7 is a detail of the latch for holding the copyholder in the folded position and is taken on line 7—7, Figure 3.

Figure 8 is a side elevation of the operating key showing a modified form of actuator spring.

Figure 9 is a section taken on line 9—9, Figure 8.

Figure 10 is a section taken on line 10—10, Figure 8.

My improved copyholder, as illustrated in the attached drawings, comprises generally a base 5, an easel 6 pivotally mounted thereon and provided with suitable supports for the notes or documents to be transcribed, a marker 7 movable along the surface of the easel for indicating the line from which the operator is copying, and mechanism for moving the marker including a manually operable key 8.

Referring more particularly to the drawings, the base 5, in the preferred form, is an L-shaped sheet metal stamping comprising arms 10 and 11. The edges of base 5 are formed over to provide a C section for rigidity. Rubber feet 12 may be pressed into suitable apertures punched in flanges of the C sections. Supports 13, rigidly mounted on arm 10 or formed integrally therewith, are each provided with a notched boss 14 and a circular aperture 15.

The easel 6 may be a solid rectangle, or, as here shown in the preferred form, it may be cut away to form the legs 17. The easel 6 is formed of sheet metal, stamped or pressed to shape with edges 18 beaded for the purpose of obtaining rigidity, and may be provided with corrugations (not shown) to obtain additional stiffness. The supports 19, rigidly secured to easel 6 or formed integrally therewith, are each provided with a notched boss 20 and a circular central aperture 21. A bearing rod 22 headed at one end and threaded at the other to accommodate a knurled nut 23 is inserted in the apertures 15 and 21 to pivotally secure the easel 6 to the base arm 10. When the knurled nut 23 is tightened, the notched bosses 14 and 20 which have complementary faces are drawn into engagement and are thus adapted to hold the easel 6 at a desired angle to the base 5. A permanent stop 25 comprising a substantially triangular piece of metal is rigidly secured by suitable means to the back of each leg 17 and limits the backward movement of the easel 6, as appears particularly in Figures 2 and 5.

A substantially L-shaped combination spring 55

latch and stop 26 for holding the easel in its folded position is shown in operative position in Figures 3 and 7 and may be formed by bending a piece of sheet metal. The upright portion 5 27 of latch 26 is provided with a triangular protuberance 28 which is notched as at 29 and bent at right angles to the upright portion 27. The latch 26 is rigidly fastened by suitable means, here shown as rivets 30, to arm 11 adjacent its 10 forward end. When the easel 6 is folded down on base 5, the edge 18 strikes the surface 31 of latch 26 and cams the latch outward until the notch 29 engages the edge 18 when further movement of the easel is arrested. To release the 15 easel 6, the latch 26 is pressed outward, thus freeing the edge 18 from the notch 29.

The easel 6 is provided with a clamping bar 32 for paper or the like positioned adjacent the top thereof. The clamping bar 32 is mounted at 20 its ends in supports 33 provided with apertures 34. The clamping bar 32 is bent in the form of a wide shallow U, as clearly indicated in Figure 4, and may be provided with rubber rollers 35. Coiled springs 36 are provided for urging the 25 clamping bar 32 into yielding contact with the easel 6.

A substantially L-shaped bar 37 for supporting a notebook is pivotally mounted in apertures formed in supports 38 positioned adjacent the 30 left-hand side at the upper portion of easel 6, as shown in Figure 1. When not in use, the bar 37 may be removed from the supports and reinserted with the long shank of the L passing through the supports, in order to place it in a 35 position where it will not obstruct the easel 6 or protrude unduly at one side of the device when it is desired to use the clamping bar 32. A portion of a notebook of the well known spiral wire bound type is shown in dotted lines in Figure 4, with the 40 wire binding slipped over the right-hand end of rod 37, but it will be obvious that any ordinary stenographer's notebook could be folded over the rod.

The mechanism for actuating the marker 7 will 45 now be described and includes a pair of brackets 42 mounted at the right-hand side of the easel 6. A stationary guide rod 43 is secured to the brackets 42 by suitable means here shown as cap nuts 44. An actuator rod 45 is slidably mounted in the 50 brackets 42 parallel to the guide rod 43. A connecting link 47 is pivotally joined to the actuator rod 45 adjacent the lower end of said rod 45 below the lower bracket 42. The other end of the connecting link 47 is pivotally mounted at 48 in the 55 bell crank lever 49, which in turn is pivotally mounted in the support 50 which is secured to the base 5. The radius rod 51 has one end pivotally connected to the bell crank lever 49, as at 52. The opposite end of the radius rod 51 is provided 60 with an enlarged portion 53 provided with a transverse aperture 54.

A key lever 60 is pivotally mounted on a suitable support 61 which is secured adjacent the forward end of the base arm 11. The key 8, which 65 may be of any convenient shape and is here shown as an oblong bar, is secured to the key lever 60, which is here shown as substantially triangular in shape although it may be in the form of a bell crank lever. A slot 63 is provided in the key lever 70 60 and is located directly above the pivotal connection 61' of the key lever 60 to the support 61. In the preferred form, the slot 63 is made on an arc having a radius equal to the effective length of the radius rod 51. A slide block 65 adapted to 75 slide in the slot 63 is provided with an externally

threaded extension 66. A knurled nut 67 internally threaded to match the threaded portion 66 is provided with an extension 68. The extension 68 is adapted to fit into the aperture 54 of the enlarged portion 53 of connecting rod 51 to permit 8 a pivotal connection. By tightening the knurled nut 67, the slide block may thus be secured at any point within the slot 63 while permitting rotational movement between the radius rod and the key lever. The stop 69 is secured to the base arm 10 11 beneath the key lever 60 to limit the downward movement of the key.

A spring 70 is provided to yieldingly maintain the key lever 60 and the associated actuator rod 45 in their normal raised positions. In the preferred form, the spring 70 comprises a plurality of coils 71 with projecting ends 72 and 73 which are fastened respectively to the key lever 60 and the base arm 11, as best shown in Figure 2. The coiled part 71 of the spring 70 may be supported 20 on the pivotal connection 61' which projects outwardly from the support 61.

A clutch box 75 is formed of a piece of channel shaped metal. Apertures are provided in the flanges of the channel to correspond in size and 25 spacing with the guide rod 43 and the actuator rod 45 so that the clutch box may slide freely on these rods. A jam clutch 76 is formed with an arm 77 having an aperture 78 adjacent the end thereof and a second arm 79 which is bent at right 30 angles to the arm 77 and provided with an aperture 80 to receive the actuator rod 45 shown in Figures 4 and 6. The clutch member 76 is pivotally secured to the clutch box by means of the stud 81 passing through the aperture 78. The 35 end of the arm 79 is extended outward beyond the side of the clutch box 75 to provide a finger piece for manually releasing the jam clutch 76 when desired. A similar jam clutch 82 is mounted on the same stud 81 to engage the guide rod 43. 40 Springs 83 and 84 are provided to positively operate the jam clutches 76 and 82, respectively, and a stop 85 is provided to limit the upward movement of the jam clutches.

A stop 86 is secured to the easel 6 so as to 45 project into the path of the finger piece of the clutch 76 as the clutch box reaches the bottom of its travel. The clutch 76 is thus released so that continued actuation of the rod 45 will not damage the mechanism.

The marker 7 is pivotally mounted on the clutch box 75 by means of the L-shaped rod 87 which is let into suitable apertures 88 provided in the flanges of the clutch box 75. A retaining means 89, here shown as a cotter pin, is provided 55 to secure the rod 87 in the clutch box 75. A catch 90 is provided to hold the marker 7 in its lowermost position against the easel when folding the machine.

In assembling, the guide rod 43 is threaded 60 through the apertures provided in the flanges of the clutch box 75 and the aperture provided in the jam clutch 82. The actuator rod 45 is threaded through the holes provided for it in the flanges in the clutch box 75 and through the aperture 80 of the jam clutch 76.

When the key 8 is depressed, the key lever 60 pivots about its support 61' compressing the spring 70, and pulls the radius rod 51 forward, which in turn operates the bell crank 49 to draw 70 the connecting link 47 and the actuator rod 45 downward. When the actuator rod 45 starts downward, the jam clutch 76 grips the actuator rod, moving the clutch box with it. The downward movement of the clutch box releases the jam 75

clutch 82 from the guide rod 43. When the key 8 is released, the spring 70 returns both the key and the actuator rod 45 upward to their normal positions. Jam clutch 82 seizes on the guide rod 43, thus preventing the clutch box from moving back upward. Jam clutch 76 is released with the upward movement of the actuator rod 45 thus allowing the rod to slide upward freely.

Spacing adjustment is obtained by changing the position of the slide block 65 in the slot 63. When the slide block 65 is at the bottom of the slot 63, the movement transferred from the key 8 to the radius rod 51 is a minimum. As the slide block is raised in the slot 63, the amount of motion transmitted to the radius rod 51 is increased to a maximum when the slide block 65 is at the top of the slot 63. Infinite change between maximum and minimum limits in the spacing of the marker 7 may be obtained by changing the position of the slide block 65 in the slot 63 without affecting the movement of key 8, which remains constant.

To adjust for a particular spacing, the copy is first secured to the easel 6 either by means of the clamp bar 32 or the notebook holder 37. The marker 7 is then placed on a line of the copy. This is most easily accomplished by lifting up on the projecting ends of the jam clutches 76 and 82 with the thumb and finger of one hand. When the clutches are thus released, the clutch box 75 and the associated marker 7 may be slid upward or downward to a desired position.

The knurled nut 67 is next released and the slide block 65 dropped to the bottom of slot 63. The key 8 is then depressed until the key lever 60 strikes the stop 69. This will move the marker 7 downward the minimum distance. With the key 8 held in the depressed position, the slide block 65 is raised in the slot 63 until the marker 7 is moved downward to the next line of the copy. Then the knurled nut 67 is tightened and the spacing will be constant until a re-adjustment is made. By this system of adjustment, exact spacing corresponding to the spacing of the copy is obtained by adjusting to the copy itself.

It may be noted here that the marker 7 is pivoted to the clutch box 75 which is carried adjacent one edge of the easel 6, and the notebook holder 37 is pivoted adjacent the opposite edge 50 of the easel. This construction permits swinging the notebook outward to turn a page and at the same time the marker 7 is swung out of the way on its pivot. When the notebook is swung back against the easel, the marker will swing 55 back into its operating position at a mere touch on the part of the operator.

It is to be noted that with the arrangement of spring 70 shown in Figure 2, the force needed to compress the spring when the key is depressed is constant regardless of the setting of the slide block 65 to vary the spacing, since the amplitude of key motion is constant. A slight change in operating force is required, however, with changes in setting of the slide block 65, due to 65 the weight of the actuator rod 45 operating on the key through the connecting mechanism.

Although the change thus required in operating pressure in the construction above described is not considered of great moment, a modified form of key lever spring and spacing adjusting mechanism is shown in the Figures 8, 9 and 10, which is adapted to automatically change the spring pressure with change in spacing to maintain the operating force substantially constant. In this modified form, the spring 95 may be a

leaf spring anchored at its lower end 96 in an adjustable mount 97. The spring 95 extends vertically substantially the height of the adjusting slot 63.

The mount 97 is here shown as a short shaft 5 provided at one end with a slot 98 to receive the end 96 of spring 95. A reduced portion 99 of the shaft 97 has its free end threaded to accommodate a knurled nut 100. A suitable aperture 101 is provided in the support 61 to accommodate the portion 99 of shaft 97. The slide block 65 is provided with a slotted extension or fork 102 adapted to engage with the spring 95.

In assembling, the spring 95 is secured in the slot 98 of the mount 97. The reduced portion 15 99 of the mount 97 is then inserted in the aperture 101 and the spring 95 inserted in the fork 102 of slide block 65. The knurled nut 100 is then threaded on the shaft. Initial tension of the spring 95 is adjusted by rotating the mount 97 20 and is then secured by tightening the nut 100. A notched boss 103 may be provided on support 61 to cooperate with notches on mount 97 for locking the mount in position when nut 100 is tightened. 25

When the slide block 65 is raised or lowered to change the spacing, the fork 102 will engage the spring 95 at greater or less distance from the mount 97 thus changing the spring pressure to correspond with the change in leverage of the key and maintain a fixed value of finger pressure for all settings of the slide block. 30

Although I have shown and described a particularly simple construction, it is obvious that many of the details may be changed without departing from the spirit of my invention, and I wish to be limited only by the scope of the appended claims. 35

I claim:

1. In a copyholder having a base, an easel for supporting the copy and a movable marker, in combination, a key including a finger piece pivotally mounted on said base located a substantial distance from said easel, means for moving said marker a predetermined amount, means including a radius rod for transmitting movement of said key to said marker, and means positioned adjacent the fingerpiece of said key for varying the amount of movement transmitted by said connecting rod while the amount of movement of said key is maintained substantially constant. 40

2. In a copyholder having a base, an easel for supporting the copy and a movable marker, in combination, said base including a forwardly extending arm positioned adjacent one side thereof, an operating key including a finger piece pivotally mounted adjacent the forward end of said arm, means carried by said easel adapted to progress said marker step by step downwardly of said easel, means including a connecting rod for transmitting motion from said key to said means for progressing said marker, and means positioned adjacent the finger piece of said key for varying the amount of movement transmitted by said connecting rod while the amount of movement of said key is maintained substantially constant. 55

3. In a copyholder having a base, an easel for supporting the copy and a movable marker, in combination, an operating key having a constant length of stroke, means for transmitting motion from said key to said marker and adjusting means associated with said means for transmitting motion so constructed and arranged as to vary the 60 70 75 80 85 90 95 100 105 110 115 120 125 130 135 140 145 150 155 amount of motion transmitted from said key while maintaining said key stroke constant.

4. A device as described in claim 3 wherein said adjusting means includes a slotted lever and 5 a connecting rod and wherein said slot is arcuate in shape, the radius of said arc being the length of said connecting rod.

5. In a copyholder having a base, an easel for supporting the copy and a movable marker, in 10 combination, means for progressing said marker in substantially equal steps, means for adjusting the amplitude of said steps including a bell crank lever pivoted intermediate the bell crank arms to said base, said lever having a constant amplitude 15 of motion, a slide member mounted on one of said bell crank lever arms, releasable means for securing said slide member to said arm at substantially any point along its length from adjacent the pivot point to the free end of said arm, 20 and a connecting link for transmitting motion from said slide member to said means for progressing said marker.

6. A device as described in claim 5 wherein said bell crank arm is slotted to secure and guide 25 said slide member.

7. In a copyholder having a base, an easel for supporting the copy and a movable marker, in combination, means for progressing said marker in substantially equal steps, said means including 30 a key having substantially constant amplitude of motion, and means for obtaining infinite variation between maximum and minimum limits of the amplitude of said steps.

8. In a copyholder having an easel, longitudinal 35 ways positioned on the easel adjacent one edge thereof, and a traveller adapted to slide on said ways, in combination, a marker pivotally mounted adjacent one end on said traveller to permit the free end of said marker to swing outwardly and 40 at right angles to said easel, and a notebook support comprising a rod pivoted at one end, said pivot being supported on said easel adjacent the top thereof and adjacent the edge opposite said longitudinal ways.

45 9. A device as described in claim 8 wherein said notebook support is demountable.

10. In a copyholder having a base, an easel for supporting the copy, a movable marker and oper-

ating means for spacing said marker step by step longitudinally of said easel, in combination, a key for said operating means pivotally mounted in said base, adjusting means adapted to vary the amount of motion transmitted from said key to 5 said marker, a spring adapted to yieldingly maintain said key in its normal position, and means associated with said motion adjusting means for automatically varying the spring pressure of said spring as said motion adjusting means is varied. 10

11. A device as described in claim 10 wherein said spring comprises a leaf anchored at one end.

12. A device as described in claim 10 wherein said spring is provided with means for adjusting the initial tension of said spring. 15

13. In a copyholder having a base, an easel for supporting the copy, a movable marker and operating means for spacing said marker step by step longitudinally of said easel, in combination, a key for said operating means pivotally mounted on 20 said base, adjusting means adapted to vary the amount of motion transmitted from said key to said marker, said adjusting means including a lever pivotally mounted adjacent one end thereof, a slide member mounted on said lever, means for 25 releasably securing said slide member to said lever along its length from adjacent said pivot point to its free end, a leaf spring anchored at one end positioned adjacent said lever and parallel thereto, and means for varying the pressure of 30 said leaf spring carried by said slide member and including a fork adapted to operatively engage with said spring.

14. In a copyholder having a base, an easel for supporting the copy, a movable marker and operating means for spacing said marker step by step longitudinally of said easel, in combination, a key for said operating means pivotally mounted on 35 said base, adjusting means adapted to vary the amount of motion transmitted from said key to 40 said marker, said adjusting means including a lever pivotally mounted adjacent one end thereof, a slide member mounted on said lever, and means for releasably securing said slide member to said lever along its length from said pivot point to its 45 free end.

PHILIP P. GLASSEY.
